ABSTRACT: A wire element is electrically tuned so that it operates with a low impedance. Bit information is then readily transferred along the wire from one location (sender) to another location (receiver) by energizing the drive strap adjacent the sending bit with a burst of pulses. When the circulating current in the wire builds up to a maximum value, the drive strap adjacent to the receiver bit is energized with a single pulse. The receiver bit will then switch if its binary state is opposite to that of the bit at the transmitter.

TUNED PLATED WIRE CONTENT ADDRESSABLE MEMORY

The instant application is related to applications having Ser. Nos. 466,904, now U.S. Pat. No. 3,487,380, 475,941 now U.S. Pat. No. 3,449,731 and 499,971 now U.S. Pat. No. 3,460,114 by Woo F. Chow and Ser. No. 671,645, now U.S. Pat. No. 3,524,174 by Carlos F. Chong.

This invention relates in general to memory devices and in particular to plated wire memory devices for use in content addressable memories.

One of the difficulties encountered in transferring information along a small diameter plated wire memory device has been that the impedance of the latter is relatively high. The prior art techniques have involved using mechanical expedients to lower the plated wire impedance. These techniques involve essentially making the plated wire into a coaxial line. In view of the small size of the wire and the difficulty in forming this wire into a coaxial line, the prior art mechanical arrangements have not been entirely satisfactory.

In summary, this invention relates to an arrangement for reducing the impedance of a plated wire memory element, which is primarily inductive, by tuning out the latter with a capacitor. This arrangement enables the wire memory to operate in a relatively low impedance mode. Information is readily transferred along the wire from one bit position to another bit location by first applying a burst of square waves to the sender strap (i.e., transmitter) located adjacent one bit of information. When the current in the wire has built up to a maximum, the receiver drive strap which is juxtaposed to a second bit location is energized with a single pulse. If the information adjacent the sender strap is different from the information adjacent the receiver strap, the information in the latter is switched. In the event that the bit information at the sender location is identical to the receiver location, there will be no switching of information. Accordingly, information can be readily transferred from one location to another location along the plated wire.

Accordingly, it is an object of this invention to provide a new and improved arrangement of a content addressable memory using plated wire memory elements.

It is a further object of this invention to provide for a new and improved plated wire content addressable memory which will allow for easier mechanical construction.

It is yet a further object of this invention to provide for a new and improved plated wire content addressable memory which will enable longer plated wires and larger work lengths to be employed.

Referring now to the drawings, FIG. 1 depicts an exemplary device which utilizes the instant invention.

FIG. 2 further depicts the various signals applied to the device in FIG. 1.

Referring now to FIG. 1 in greater detail, plated wires 10 and 12 are plated magnetizable wires which comprise 5 mil beryllium copper substrates upon which is coated a Permalloy film. The Permalloy film is deposited with a thickness of approximately 10,000A and is deposited with the property of uniaxial anisotropy. The property provides an EASY axis which is circumferential to the wire and a HARD axis which is along the length of the wire.

Connected in series with the respective plated wires 10 and 12 are the capacitors 18 and 20. The capacitors 18 and 20 are tuning capacitors and are selected to tune out the inductance of the wires 10 and 12. In other words, the impedance to current in the wires 10 and 12 is primarily inductive and the tuning capacitors 18 and 20 eliminate the effect of this inductance. Therefore, the current in the wire is limited only by the resistance. One foot of wire would have approximately 1.5 ohms of the resistance.

Arranged orthogonally to wires 10 and 12 are the drive straps 14 and 16. The width of the straps 14 and 16 is determined by the amount of current that is to be generated in the plated wires 10 and 12. In other words, the amount of magnetic material underneath the straps 14 and 16 that is switched when the respective straps are energized determines the

amount of current that will be induced in the plated wires. This aspect will be discussed in greater detail below. The drive straps 14 and 16 are shown connected to the driver and timing circuit block 11. In the exemplary embodiment of FIG. 1, the drive strap 14 is connected to a multipulse generator source whereas the energizing means connected to the drive strap 16 is a single pulse generating source. As will be explained in greater detail with respect to FIG. 2, the respective energizing means applied to straps 14 and 16 are applied at different times and hence a timing circuit is also required and is included within block 11. Since the driver energizing source and the timing circuit 11 are well known in the art, they will not be further discussed.

At the intersection of the respective drive straps 14 and 16 and the plated wires 10 and 12 there is stored binary information (i.e., a "0" or a "1"). Whether a binary "0" or "1" is stored at the intersection of the plated wire and the drive strap is determined by the orientation of the magnetization vectors. In other words, a clockwise orientation of the magnetization vectors (as viewed from the right end of the wire looking toward the left) may represent a binary "1" and a counter-clockwise orientation of the magnetization vectors may represent a binary "0". Thus, at intersections 22 and 24, respectively, a "1" is stored (as represented by the clockwise vectors 15 and 19).

Information is transferred along the plated wires 10 and 12, that is, from location 22 to location 24 and from location 23 to location 25 in the following manner. It is to be understood that other plated wire arrangements may be utilized for this transfer and FIG. 1 is merely exemplary. For example, a reference strap may be utilized with the transmitter strap in order to supply one-half of the current. To transfer information from location 22 to location 24, a burst of pulses shown in FIG. 2a is first applied to the drive strap 14 by means of the driver and timing circuits 11. The application of the burst of pulses to the transmitter drive strap 14 causes the magnetization vector 15 to oscillate to the position shown by the vector 15a and back again to its quiescent point. This oscillation back and forth includes a voltage in the plated wire 10 which approximates a sine wave as shown in FIG. 2b. The output voltage induced in the plated wire generates an oscillatory circulating current in the plated wire 10 whose polarity depends on whether a "1" or "0" is stored (see FIG. 2c). When the frequency of the pulses in a burst corresponds to the resonant frequency of the plated wire, the circulating current builds up to a value which is limited only by the DC resistance of the plated wire. When the circulating current has built up to its maximum value, the receiver strap 16 is energized with a single pulse as shown in FIG. 2d. The circulating current in the wire will cause the receiver strap 16 to switch the information at location 24 if its binary state is different from the binary information at location 22. This is accomplished in the following manner.

The solid output line in FIG. 2c represents the output current for the binary "1" stored at location 22. The single pulse (FIG. 2d) applied to drive strap 16 occurs during the half cycles, A-B and E-C (FIG. 2c). This single current pulse causes the magnetization vectors 19 at location 24 to rotate to the position 19a, which is some angle less than 90°. The current generated during the half-cycle A-B is positive and flows from the right end to the left end in plated wire 10. This positive current is a steering current and causes the magnetization vector at position 19a to be tipped back to the quiescent position shown by the vector 19. In other words, since the transmitter information is a binary "1" and the receiver information is a "1," there is no switching of the information and therefore, in essence, the "1" at location 22 has been transferred to location 24.

Referring now to plated wire 12, the "0" information at location 23 will be transmitted to location 5 in the following manner. The burst of signals shown in FIG. 2a is again applied to the transmitter strap 14 by the driver and timing circuits 11. This causes a voltage to be induced in plated wire 12 which is

180° out of phase with that shown in FIG. 2b. Accordingly, the current in the wire is oscillatory and is shown by the dotted wave forms shown in FIG. 2c. This oscillatory current flows in a positive and negative direction as shown. When the frequency of the pulses correspond to the resonant frequency of the word loop, the circulating current shown depicted FIG. 2c builds up to a maximum value. When this maximum value occurs, the drive strap or receiver strap 16 is energized by the driver and timing circuits 11 during a period shown in FIG. 2d. By applying the single pulse to strap 16 the magnetization vector 21 rotates to the position 21a (the position less than 90°). The current produced during the half-cycle E-C (FIG. 2c) will produce the negative going signal which flows from the left to the right in plated wire 12. This steering current will tip the magnetization vector 21a to the position 21b. In other words, the transmitter strap 14 has transferred the "0" information at location 23 to the receiver location 25 by switching the binary "1" into a binary "0".

As was previously discussed, the capacitor connected to the plated wire tunes out the inductance and the current is limited only by the resistance. Thus, for a 35 millampere steering current down one foot of wire, which has a 1.5 ohm resistance, we need 52 millivolts from one strap. Since 35 mils of strap gives about 10 millivolts, about 175 mils of strap width are required of one transmitting strap supplies all of the current. If the transmitting strap supplies one-half of the current with the other one-half being supplied by a reference strap, a strap width of 87.5 mils is required. It should be noted that the number of pulses in the burst and the frequency of the burst are dependent upon the characteristics of the plated wire capacitor resonant circuit. The resonant frequency of the plated wire circuit is

$$F = \frac{1}{2\pi\sqrt{LC}}$$

where L is the inductance of the plated wire and C is the value of the capacitor in the word loop. Therefore, the frequency of

the burst should correspond to the resonant frequency of the word loop.

I claim:

1. A memory arrangement comprising, a wire substrate having a ferromagnetic coating deposited thereon for storing binary information, said coating being deposited with an EASY axis of magnetization which is circumferentially oriented, means coupled to either end of said substrate for electrically tuning said memory, said wire being thereby operated in a low impedance mode, at least first and second juxtaposed conductors positioned substantially orthogonal to said wire substrate, the intersection of said first conductor and said memory comprising a first information bit and the intersection of said second conductor and said memory comprising a second information bit, said first conductor being energized with a burst of pulses and said second conductor being energized with a single pulse, information being thereby transferred from said first bit location to said second bit location during the application of said single pulse.
2. The memory arrangement in accordance with claim 1 wherein said information transfers from said first bit location to said second bit location is accomplished nondestructively.
3. The memory arrangement in accordance with claim 1 wherein timing means are coupled to said first and second conductors for energizing the latter at different time periods, said second conductor being energized at a time that corresponds approximately to the development of the maximum current in said wire.
4. The memory arrangement in accordance with claim 3 wherein binary information is transferred by causing the rise time of the highest cycle of the current train of a first phase developed in said wire to correspond in time to said single pulse applied to said second strap and in the alternative, causing the fall time of the highest cycle of the current train of a second phase developed in said wire to correspond in time to said single pulse applied to said second strap.
